[57] CLAIM

The ornamental design for a tape drive bezel, as shown and described.

DESCRIPTION

FIG. 1 is an isometric view of the top front and right side view of a tape drive bezel showing our new design;

FIG. 2 is a front elevation view showing a column of indicator lights and push buttons on each end of the front side of the tape drive bezel of FIG. 1;

FIG. 3 is a rear elevation view of the tape drive bezel of FIG. 1;

FIG. 4 is a right-side elevation view of the tape drive bezel of FIG. 1;

FIG. 5 is a left-side elevation view of the tape drive bezel of FIG. 1;

FIG. 6 is a top view of the tape drive bezel of FIG. 1; and

FIG. 7 is a bottom view of the tape drive bezel of FIG. 1.
